METHOD OF DRYING THREAD OR THE LIKE

Hayden B. Kline and Louis S. Fryer, Cleveland, Ohio, assignors to Industrial Rayon Corporation, Cleveland, Ohio, a corporation of Delaware

Application September 29, 1939, Serial No. 297,074

6 Claims. (Cl. 18—54)

This invention relates to methods which may be used in manufacturing and/or processing strip material such as thread or the like (hereinafter referred to as "thread"). More particularly, the invention is directed to methods which may be employed advantageously in the manufacture and/or processing of textile thread to control certain of the physical and physico-chemical properties thereof; e. g., shrinkage, dyeing and other characteristics. The invention is especially useful in the manufacture by a continuous process of multiple filament artificial silk thread; i. e., rayon.

The use to which a completed commercial textile thread is ultimately to be put is determinative of the nature of the physical and physico-chemical properties imparted to the thread. Such properties are influenced largely by the type of treatment employed in the processing of the thread. For example, a textile thread, to be commercially acceptable for general use in the weaving industry, must almost always possess a low residual shrinkage capacity. The term "residual shrinkage capacity," as used hereinafter is defined as the amount by which a dry, finished thread will shrink, if unrestrained in any manner, upon being rewet and redried.

Commercial textile thread employed in weaving, particularly for use as a weft thread, should be of such low residual shrinkage capacity as to preclude the possibility that the fabric woven therefrom will shrink by more than a very small amount, if at all, during the subsequent finishing operations. The finishing operations ordinarily consist of washing, dyeing, etc., after which the fabric is usually dried in rigid tentering frames which hold the fabric to the desired finished width. If the residual shrinkage capacity of the thread from which the fabric is woven exceeds very low limits, the tendency of the fabric to shrink stresses the thread, causing barré effects to develop in the fabric and in some cases causing the fabric to be torn from the tentering frames. In either case, the commercial value of the fabric is seriously impaired.

Furthermore, weaving thread should have throughout its length a uniform, and preferably high, affinity for dyestuffs. Uniformity of dye affinity is important inasmuch as a woven fabric formed of thread which does not possess the desired uniformity usually embodies defects of the type known to the trade as "shiners" or "dye barré" which deleteriously affect the commercial acceptability of the fabric. It is desirable to produce a thread having high dye affinity because it

requires less time and handling to secure the desired depth of color in the finished fabric woven from such thread and because the fastness of the dyestuff is improved.

For purposes of illustration, but in no sense of limitation, certain of the features of the invention will be described hereinafter in connection with the manufacture of multiple filament viscose artificial silk thread.

Viscose artificial silk thread comprises hydrated cellulose regenerated from a solution of sodium cellulose xanthate ("viscose"). Coagulation is brought about by extruding the solution through a plurality of minute orifices into an acid precipitating bath, an operation which gives rise to a delicate thread consisting of a plurality of filaments that, at least at this stage, are more or less gelatinous in nature. Subsequent to coagulation, the thread is ordinarily subjected before it is initially dried to suitable processing treatments including washing, desulphurizing, etc. During these operations and in fact until such time as it is completely solidified and dried, the thread is usually considered to be in a "gel" state.

Great care must be exercised in processing thread while it is in the gel state inasmuch as its physico-chemical properties are markedly affected by the nature of the processing treatments, as well as by the manner in which the treatments are administered to the thread. It has been found, for example, that the manner of drying the thread initially; i. e., from the gel state, determines to a large extent the final characteristics of the finished thread, particularly its dyeing properties. This is equally true whether the thread is manufactured by the so-called continuous process or according to the discontinuous methods of production by which, until recently, all viscose artificial silk thread was produced.

Among other things, the tension imparted to the thread during its drying from the gel state affects the physico-chemical characteristics of the thread. For example, if thread is dried in the spool package in which it is collected in the spool-spinning process, uneven dyeing properties result. Such non-uniformity results from the fact that shrinkage of the innermost layers of thread is prevented by the presence of the spool, while the faster drying outer layers of thread are prevented from shrinking only by the slower drying intermediate layers. Different portions of the thread are differently stressed, resulting in widely varying dye affinities. As a rule, such irregularities render spool-dried thread unfit for

weaving purposes unless special precautions are taken to improve its uniformity.

To overcome these difficulties, it has been the usual practice in the manufacture of weaving thread by discontinuous processes to dry the thread in the form of a skein containing several thousand yards of thread. The skeins are usually formed by unwinding the thread from the package in which it was collected and rewinding it into skein form, in which state the thread can be supported so that it hangs substantially free of tension during drying. The thread can therefore shrink freely, wherefore it has a low residual capacity to shrink; however, even such skein-dried thread does not have absolute uniformity, this for the reason that the outer windings of the thread in the skein tend to dry more rapidly than the intermediate windings and therefore subject the thread to tension differences which affect its dye affinity.

On the whole, the discontinuous production of viscose weaving thread is unsatisfactory because of the high cost of production, the waste of the thread due to injuries resulting from repeated handling, and the long periods of time required in processing. The completed product does not possess the desired uniformity of shrinkage, dyeing and other characteristics, so that in general it is not capable of measuring up to the extremely high standard of quality which is desired. For such reasons, to produce viscose weaving thread commercially by a continuous process wherein such disadvantages are eliminated has long been recognized as a desideratum.

However, the continuous production of viscose artificial silk thread involves other problems not present in discontinuous methods of production. Such problems arise primarily out of the fact that in the continuous process thread in the finished state is produced from liquid viscose in a very small fraction of the time required in discontinuous processes. Whereas in discontinuous processes thousands of yards of thread wound in a package are subjected to processing conditions for many hours or even days, in the continuous process not more than a few yards of thread are subjected to a given set of processing conditions simultaneously. In particular, the shortness of the time available for the initial drying of the thread from the gel state is a factor causing difficulties in the manufacture of thread by a continuous process.

In the continuous process of manufacture, it has been found that the rapid initial drying of the thread from the gel state does not give rise to a permanently low shrinkage capacity, this even if the thread is permitted to shrink during such drying operation. The residual shrinkage capacity of thread dried under such conditions is often so high that the thread is not well adapted to weaving on looms producing fabrics of widths approximating the intended finished width of the fabric. These difficulties are probably related to the fact that in the continuous process the thread is dried in only a few seconds or, at the most, a minute or two. Such difficulties are not found in the manufacture of weaving thread by discontinuous processes.

It has therefore been thought that, while the continuous process constitutes a very great improvement over the discontinuous processes in respect of uniformity of the thread, amount of labor required, and reduced production time, it does not lend itself to the production of thread of a permanently low residual shrinkage capacity.

However, the present invention, in addition to obviating the numerous disadvantages of the discontinuous process, gives rise to a thread which is eminently suitable for weaving, which is of a particularly high degree of uniformity of physical and physico-chemical characteristics, and which is characterized by a permanently low residual shrinkage capacity. The invention makes these results possible by repeatedly drying and rewetting the thread in a continuous process while permitting it to shrink, all as more fully explained hereinafter. For convenience, the invention will be described as applied to the manufacture of multiple filament viscose artificial silk thread on apparatus operating on the principle of that shown, described and claimed in copending application Serial No. 7,114, filed February 18, 1935 (Patent 2,225,642).

In the drawings, Figure 1 represents a sectional elevation of one form of apparatus in which the invention is embodied. Figure 2, which represents a portion of the apparatus of Figure 1 on an enlarged scale, shows the means for repeatedly wetting and drying the thread according to the invention. Figure 3 illustrates on the same enlarged scale a similar portion of modified apparatus likewise embodying the invention. Figure 4 is an end elevation of one form of thread-advancing reel employed to dry the thread. Figure 5 represents a sectional elevation of said reel from line 5-5 of Figure 4. Figure 6 is a sectional elevation of another type of thread-advancing reel employed to dry thread after intermediate rewetting.

Figure 1 shows a complete machine for continuously manufacturing multiple filament viscose artificial silk thread of low residual shrinkage capacity in accordance with the teachings of the present invention. Said apparatus, a portion of which is shown in greater detail in Figure 2, is adapted to produce a large number of threads simultaneously, each by the extrusion of viscose from a spinneret 2 disposed in a coagulating bath 3 contained in trough 4. Each thread 1 passes to a thread-advancing reel 5, the same being the first of a concatenate series of thread-advancing reels designated 5 to 14, inclusive.

In the apparatus of Figures 1 and 2, the thread-advancing reels 5 to 14, inclusive, take the form of reels of cantilever construction operating on the principle of that described in said copending application No. 7,114 (Patent 2,225,642). Each of reels 5 to 14, inclusive, advances the thread toward the unsupported end thereof in a large number of closely spaced, generally helical turns. On said reels suitable liquid processing operations such as washing, desulphurizing, etc., are performed on the thread, after which the thread is dried. From the last reel 14, the thread passes to suitable collecting apparatus, such as the cap-twister 16, which collects the finished thread in package form.

In said apparatus, each thread-producing unit comprises a spinneret, a descending series of reels 5 to 14, inclusive, and an associated cap-twister. The reels in each descending series are disposed in stepped arrangement with the unsupported or discharge end of each preceding reel in apposite relation to the supported or receiving end of the succeeding reel, the unsupported ends of all reels extending in the same direction. A plurality of such thread-producing units is disposed on each side of the apparatus; so that the apparatus as a whole has two operating faces, one on each side thereof. Corresponding parts of all units on each

side of the apparatus are therefore in corresponding positions lengthwise thereof.

The use to which the finished thread is to be put is largely determinative of the nature of the processing treatments and the manner of administering the treatments to each of the threads 1. In the illustrated apparatus, the thread 1 is drawn upward by reel 5, on which a relatively long length of the thread is continuously but temporarily stored in order to provide sufficient time for the thread to achieve the desired degree of coagulation before it is subjected to subsequent processing treatments. The thread then passes from the unsupported end of reel 5 to the supported end of succeeding reel 6.

On reel 6, the thread may, if desired, be subjected to the action of an additional coagulating liquid. Wash water may next be applied to the thread on reel 1, after which any free sulphur which may be produced in the thread as a result of the regeneration process may be removed by the application to the thread on reel 8 of a suitable desulphurizing liquid. The thread may be washed again on reel 9 to free it of the desulphurizing medium and, if desired, may be bleached on reel 10. The thread 1 then passes to reel 11 on which it may again be washed.

In the embodiment of the invention illustrated in Figures 1 and 2, the liquid to the action of which the thread is subjected on reel 6 is supplied from a reagent distributor 17 communicating with a supply pipe 18 which extends longitudinally of the apparatus on each side thereof. Similarly, the liquid supplied to each of the succeeding reels 7 to 11, inclusive, is applied to the thread from a reagent distributor 17 communicating with a conduit 19 which extends longitudinally of the machine, being formed integrally with the lower portion of collecting trough 21 disposed beneath the preceding reel. Collecting troughs 21 are disposed beneath all the reels from which liquid drips from the thread, such liquid being recirculated and reused.

The various processing liquids are applied to the thread on reels 6 to 11, inclusive, at the unsupported end of each reel in such manner as to form a traveling film of liquid extending uninterruptedly around the entire thread-bearing periphery of the reel. In the illustrated apparatus, the reels are inclined to the horizontal in order that such film of liquid may travel along each reel from the unsupported end toward the supported end thereof, thus providing a counter-current flow of liquid which more effectively processes the thread. Although these conditions do not occur on reels 12 and 13, it is convenient from a constructional standpoint to tilt them also. According to the present invention, after the aforementioned treatments have been performed, the thread is dried on reels 12, 13 and 14, as explained hereinafter.

After thread 1 has been completely processed, it is passed from the last reel 14 to cap-twister 16 by means of which it is twisted and collected. The collecting apparatus comprises a continuous belt 22, driven by rotating drum 23, which belt, guided by suitable pulleys, passes around the whisks 24 of cap-twisters 16 on opposite sides of the apparatus, thus rotating the bobbins 25 mounted on the whisks of such cap-twisters. Lifter rails 26 actuated by a suitable cam mechanism (not shown) reciprocate bobbins 25 into and out of caps 27 of the cap-twisters, thus twisting the thread and collecting it on bobbins 25 in package form. Such cap-twisting apparatus

forms no part of the present invention, but is shown, described and claimed in copending application Serial No. 241,222, filed November 18, 1938 (Patent 2,203,665).

According to the invention, thread which has been formed as above described but which is still in the gel state is subjected to repeated drying with intermediate rewetting on a plurality of reels under conditions permitting shrinkage of the thread in the course of at least one drying operation. During the time that the various liquid processing treatments are being administered to the thread on the reels prior to reel 12, the thread is always in the gel state. On reel 12, however, the thread is subjected to its initial drying operation, being dried by means of heat applied to the reel from the interior thereof. After being dried on reel 12, it is rewet, stored under conditions such that excess liquid carried by the thread may drip therefrom on reel 13, and dried once again on reel 14.

While various modifications thereof may be employed, the apparatus shown in Figure 2 has been found to be extremely satisfactory for these purposes.

In said apparatus, each of the drying reels 12 and 14 is formed of metal, being heated internally thereof by the means hereinafter described. The thread passing from reel 11 to reel 12 is substantially completely dried on reel 12, but just before it leaves said reel at the unsupported end thereof it is subjected to the action of a small stream of an aqueous rewetting liquid supplied from reagent distributor 29. The liquid thus applied to the reel is not sufficient in amount to spread over the reel but only to wet the last few turns of thread on the reel; however, the amount of liquid is sufficient to wet the thread thoroughly. The wet thread then passes to the reel 13 which, in the embodiment of the invention illustrated in Figure 2, constitutes a drip reel.

No processing medium is applied to the thread on reel 13; instead, the liquid applied to the thread just before it leaves reel 12 is permitted to drip therefrom. In view of the length of thread which is stored in this manner, drops of excess moisture carried by different portions of the thread which would otherwise tend to impair the uniformity of the subsequent drying operation may be removed by simply permitting them to drip from the thread. A mild evaporative action also takes place due to the exposure of the thread to the air. Consequently, when the thread reaches the discharge end of reel 13, all portions of the thread have the same or substantially the same moisture content.

The thread passing to reel 14, having a substantially uniform moisture content, may be uniformly dried on reel 14 provided that uniform drying conditions are applied to the thread. To aid in maintaining uniformity of drying conditions, an enclosure 30 is provided surrounding each reel 14. Said enclosure comprises a stationary portion 31 and a hinged closure portion 32. Slots 33 and 34 are provided at the junctions of the hinged and stationary portions to permit the thread 1 to enter and leave said chamber in passing to and from reel 14. If desired, a similar enclosure may, of course, be provided for reel 12.

Among other things, the invention contemplates that shrinkage of the thread shall be permitted to take place as hereinafter described for the purpose, for example, of imparting the de-

sired low residual shrinkage capacity to the thread.

During the initial drying of the thread on reel 12 a certain amount of shrinkage tends to occur in the thread. It has been found advantageous, but not at all necessary, to decrease the diameter of reel 12 progressively as the thread travels toward the unsupported end thereof in order to compensate for such shrinkage. The degree of taper of reel 12 should be such that for the speed of advance of the thread, the moisture content of the thread, and the particular drying conditions to which the thread is being subjected, the desired amount of shrinkage of the thread will be obtained without permitting a substantial degree of tension to develop in the thread. By providing for controlled shrinkage of the thread in this manner, the dye affinity of the thread is favorably influenced, the thread dyeing somewhat darker than otherwise would be the case.

It has been found that a slight elongation of the thread occurs when it is rewet. In the apparatus illustrated, this is compensated for by rotating the reel 13, to which the thread passes after it leaves reel 12, at a peripheral speed sufficiently greater than that of the discharge end of reel 12. With that in mind, reels 12 and 13 are rotated at the same angular speeds, but the diameter of reel 13 at its supported end is slightly larger than that of reel 12 at its unsupported end. Preferably, the ratio of the diameters is such that neither tension nor slack is developed in the thread passing from reel 12 to reel 13. The same effect may, of course, be obtained with reels of equal diameters by imposing a suitable difference on the angular velocities of the reels.

No appreciable shrinkage of the thread occurs while it is stored on reel 13; consequently, reel 13 may be formed with no variation in the diameter thereof.

Reel 14, however, is preferably provided with a contour of a character such that as the thread dries it may shrink freely. This is accomplished by forming the periphery of the reel so that it conforms closely to the shape of the diminishing helix which the thread tends to develop as it shrinks. It is known, for example, that the thread does not begin to shrink as soon as it comes into contact with reel 14, wherefore the reel may, as shown, be made substantially cylindrical for a considerable portion thereof. During this portion of the drying operation, external moisture only is being removed from the thread, the removal of which does not result in shrinkage of the thread.

Thereafter the internal moisture is removed, which results in marked shrinkage of the thread; accordingly, the reel 14 is tapered over the intermediate portion thereof. The minimum diameter of the tapered portion of the reel is such that sufficient shrinkage is permitted by the time the thread reaches the end of the tapered portion to impart to the thread the desired low residual shrinkage capacity. If desired, the tapered portion of the reel may be so formed that the dried thread has virtually no residual shrinkage capacity whatsoever.

The final portion of the reel, which is of substantially cylindrical form, serves among other things to insure substantially equal drying of the thread throughout its length. For example, portions of the thread which have not been as completely dried as other portions are enabled to complete their drying on such cylindrical portion

before they leave the reel. In general, it is desirable that the thread leaving this portion of the reel have a final moisture content in the neighborhood of 10%, more particularly since a moisture content of this order, especially at elevated temperatures, greatly facilitates twisting the thread.

Reel 14, as also reel 12, may advantageously have a contour conforming generally to that shown and described in copending application Serial No. 107,667, filed October 26, 1936 (Patent 2,203,686). The reel of said copending application is so designed that the diameter of the reel in effect diminishes in the direction of travel of the thread more rapidly than the diameters of the thread turns tend to diminish as a result of shrinkage of the thread. Consequently, substantially unrestrained shrinkage of the thread is possible in spite of unintentional variations which sometimes occur in the intensity of the drying conditions to which the thread is subjected on the reel.

According to the present invention, the apparatus as a whole is preferably so designed that little, if any, tension exists in the thread during the various drying, rewetting and redrying operations, such slight tension as happens to be present being substantially constant. This may be accomplished by relating the peripheral speeds of the various reels so that, although slack due to elongation is taken up, no stretch is imparted to the thread. The amount of tension to which the thread is subjected and the amount of shrinkage permitted in the thread during the second drying operation; i. e., while it is being dried on reel 14, has a great deal to do with the residual shrinkage capacity of the thread.

The apparatus illustrated as embodying the invention also includes another feature which is extremely useful in producing low residual shrinkage capacity in thread which is being dried continuously; namely, means for maintaining the thread for a substantial period at high temperatures under conditions of high moisture content. By such means, what may be called a cooking effect is imparted to the thread. Such effect apparently plays an important part in the re-orientation of the micellar structure of the thread necessary to obtain substantially complete shrinkage thereof at the high drying speeds employed in the continuous processing of viscose artificial silk thread.

In the embodiment of the invention illustrated in Figures 1 and 2, a pronounced cooking effect is produced at the unsupported end of reel 12: at that point, an aqueous rewetting liquid is applied to the thread while the thread is still at the relatively high temperature of the reel. To aid in the cooking effect, a higher temperature may be employed on reel 12 than on reel 14; indeed, it has been found desirable to maintain the temperature of the drying reel 12 considerably above the boiling point of the rewetting liquid; i. e., at a temperature in excess of 100° C., and to maintain the temperature on drying reel 14 below the boiling point of the rewetting liquid, since this permits a more nearly complete shrinkage of the thread. In the practice of the invention, the rewetting liquid may be either cold or hot, but is preferably employed only after being first heated to a temperature approaching the boiling point of water.

The idea of continuously cooking the thread in the course of the continuous drying operation forms no part of the present invention but is

described and claimed in copending application Serial No. 296,930, filed September 28, 1939, by Louis S. Fryer, Emerson B. Helm, and Kenneth M. McLellan.

While the embodiment of the invention shown in Figures 1 and 2 is preferred, apparatus embodying the invention in modified form may also be employed. Thus in Figure 3, which represents a portion of a continuous processing apparatus generally similar to that shown in Figure 2, the rewetting liquid is not applied to the thread on the reel 12, but is applied to the thread after it leaves said reel. More specifically, the rewetting liquid is applied to the first few turns of thread on reel 13. It is applied by means of a reagent distributor 29a supplied from a conduit 19 forming part of the trough 21 disposed below the preceding reel. The remainder of reel 13, on which portion no liquid of any kind is applied to the thread, serves as a drip stage for equalizing the moisture content of the thread, precisely as has been explained above in connection with reel 13 of Figure 2.

The rewetting liquid applied to the thread on reel 13 may be at room temperature but preferably is heated, since this produces a cooking effect generally similar to that produced at the unsupported end of reel 12 in the embodiment of the invention shown in Figure 2. However, somewhat better results are obtained when the rewetting liquid is applied to the thread while the thread itself is heated. In the embodiment of Figure 3, the reel 12 is shown as having no taper to compensate for the tendency of the thread to shrink, each reel member being substantially cylindrical in form. As has been explained above, tapering reel 12 has relatively little effect on the residual shrinkage capacity of the thread. In all other respects, the embodiment of the invention shown in Figure 3 is similar to that shown in Figure 2.

As is apparent from Figures 4 to 6, inclusive, each of reels 12 and 14 comprises two wholly rigid reel members, each such reel member being of substantially circular cross section. Each reel member has a periphery made up of a plurality of longitudinally extending bar members which are interleaved with the bar members of the other reel member. The two reel members rotate about axes displaced from and inclined to each other in such manner as to advance the thread in a large number of closely spaced, generally helical turns from the supported end to the unsupported end thereof.

Reel 12, as can be seen from Figures 4 and 5, comprises two rigid reel members 35 and 36 each of which is substantially circular in cross section. Member 35, which may be termed the concentric member, is mounted concentrically upon and for rotation with hollow drive shaft 37. Its periphery is made up of a plurality of spaced, longitudinally extending bar members 38. Member 36, which may be termed the eccentric member, is rotatably mounted with its axis inclined to but in a plane slightly offset from the axis of reel member 35. Its periphery includes a plurality of spaced, longitudinally extending bar members 39 alternately disposed with respect to bar members 38 of concentric reel member 35.

Concentric member 35 may be formed as shown with the bar members 38 integral with hollow body portion 40. In the illustrated reel, front and rear members 41 and 42, respectively, form fluid-tight junctions with hollow body portion 40. Said members also surround hollow shaft 75

37. Cooperating annular sealing members 43 disposed in recesses 44 in members 41 and 42, which sealing members are wedge-shaped in cross section, operate to prevent the escape of fluid past the shaft from the interior of reel member 35.

5 A bolt 45, holding a washer 46 against the outer sealing member 43 at the unsupported end of the reel, is threaded into a plug 47 welded in the unsupported end of hollow shaft 37. A washer 48, 10 disposed on shaft 37 as by means of the snap ring 49 shown, bears against the outer sealing member 43 at the rear of the reel member 35, serving thereby to locate reel member 35 endwise on the shaft. As bolt 45 is tightened, it forces the wedge-shaped members 43 together at both ends of the reel member 35, thus effectively sealing the reel member 35. The tight fits at these points 15 on shaft 37 also provide the necessary driving engagement of member 35 with said shaft.

In the reel of Figures 4 and 5, eccentric member 36 is formed of a rigid cagelike member 50 mounted concentrically upon a rotatably mounted supporting member 51, as by bolts 52. Rigid cagelike member 50 comprises the aforementioned bar members 39 which are fixed at their supported ends to an external annular supporting rib 53 by means of which the cagelike member 50 is mounted on said supporting member 51. An annular reinforcing member 54 is fixed to the bar members 39 at their unsupported ends. Supporting member 51 is mounted on frame member 55 for rotation about an axis disposed in the desired offset and inclined relationship with respect to the axis of rotation of concentric member 35.

25 Supporting member 51 is formed so that projecting boss 56 of frame member 55, on which said member 51 is rotatably mounted by means of spaced antifriction bearings 57, is disposed within the reel proper. To this end, the rear closure member 42 of the concentric member 35 is so positioned that the boss 56 can be disposed within the reel member 35. The purpose of this arrangement is to provide a construction such that, 30 although the fluid supply and removal means are associated with said frame member 55, the overall length of the reel and its supporting member is only slightly, if at all, greater than one of the liquid processing reels 6 to 11, inclusive. Thus, a 35 reel of this type can be substituted, if desired, for any one of the liquid processing reels.

40 Reel 12 is similar to the liquid processing reels in that its frame member 55 is provided with a flanged portion 58 adapted to be held by set 45 screws 60 in a cup 59 fixed to frame 70 of the apparatus (Figure 2).

50 Drive shaft 31, on which concentric member 35 is rigidly mounted, passes through frame member 55, being journaled therein by spaced bearings 61 and 62. In the reel illustrated in Figures 4 and 5, an annular, internally toothed member 63 fixed to the inner wall of hollow body portion 40 meshes with external teeth 64 formed on supporting member 51, thus providing means for 55 driving the eccentric member from the concentric member without contact of the bar members of the reel members. The bar members, being formed of a metal such as aluminum which is chosen for its high heat conductivity, would otherwise wear easily.

60 Bevel gear 65, fixed to the rear end of shaft 31, meshes with bevel gear 66 mounted on vertically inclined drive shaft 67; similarly, each of 65 the other reels 6 to 14, inclusive, is driven from drive shaft 67.

Reel 12 is heated by the circulation of a suitable heating fluid through the hollow body portion 40 of concentric reel member 35. As is apparent from Figure 5, the frame member 55 is hollow, being constructed in such manner that it includes two compartments 68 and 69 through both of which passes drive shaft 37. Suitable sealing means 71 are provided to prevent the escape of fluid past the drive shaft from the interior of said compartments either from one compartment to the other or to the atmosphere.

The sealing means include a smooth-faced stationary member 72 against which bears a rotatable bearing member 73 urged thereagainst by a spring 74. Spring 74 is compressed between a flexible annular sealing member 75 seated on member 73 and a support 76 rigidly fixed to the drive shaft 37, as by a set screw 77. The support 76 in compartment 68 serves both seals 71 therein, while the support 76 in compartment 69 serves a single seal. Said seals aid in locating the drive shaft 37, and consequently the reel member 35, endwise of the reel.

Compartment 68 is provided with an opening 78 through which heating fluid is supplied from tube 79 connected to frame member 55. The heating fluid passes through a port 80 in the wall of hollow drive shaft 37, thence longitudinally of said drive shaft, and finally through port 82 into the interior of hollow body portion 40. The heating fluid passes out of said hollow body portion 40 through an opening 83 in hollow drive shaft 37 which opening communicates with an interior tube 84 rigidly fixed in said drive shaft.

The plug 47 at the unsupported end of hollow drive shaft 37 serves to separate the inner tube and the drive shaft and to prevent fluid from passing directly from the drive shaft to the tube or vice versa. A similar plug 85 at the rear portion of said drive shaft 37 prevents the intermixing of the entering and discharging fluid. The fluid passes from said inner tube 84 through port 86 into the rear compartment 69, from which it passes out through opening 87 to a discharge tube 88.

In the apparatus shown in Figure 2, supply tube 79 is connected to a supply conduit 89 which extends lengthwise of the apparatus in such manner as to permit it to serve a plurality of reels 12 disposed lengthwise of the machine as a whole. Similarly, discharge tube 88 communicates with a discharge conduit 90 which extends lengthwise of the apparatus to permit it to accommodate a plurality of reels 12. Regulating valves 92 may be provided, as shown, to control the flow of heating fluid through the reel 12. The heating fluid may be hot water, steam or any other suitable fluid which may be heated and circulated through the system. Other heating and circulating means than that illustrated may of course be employed.

The reel member 35 and the bar members 38 thereof are thus directly heated by the fluid circulated therethrough. The other reel member 36, and particularly the bar members 39 thereof, are heated by radiation and conduction from concentric reel member 35. This arrangement is particularly efficient for drying thread, which is one reason why reel 12 is preferred for use in the apparatus of the invention. However, reel 12 per se constitutes no part of the invention, being the subject matter of copending application Serial No. 296,937, filed September 28, 1939; by Richard F. Bergmann.

Reel 14 is similar in many ways to reel 12 and 75

operates in a generally similar manner. As appears from Figure 6, it comprises two wholly rigid reel members 35a and 36a. Concentric member 35a, the periphery of which is defined by a plurality of spaced, longitudinally extending bar members 38a, is mounted concentrically upon and for rotation with hollow drive shaft 37a. Member 36a, which may be termed the eccentric member, is rotatably mounted with its axis slightly offset from and inclined to that of member 35a. Its periphery includes a plurality of spaced, longitudinally extending bar members 39a alternately disposed with respect to the bar members 38a of reel member 35a.

Concentric member 35a is formed as shown with its bar members 38a integral with a hollow body portion 40a. Members 41a and 42a, forming fluid-tight junctions with said body portion, 40a, not only close off the ends of said body portion but serve as means for mounting the reel member 35a on drive shaft 37a. Reel member 35a is held on drive shaft 37a against a collar 49a, fixed to said drive shaft, by bolt 45a threaded into the end of said drive shaft. Packing 93, 20 which is disposed in a recess 44a in member 42a, is compressed against collar 49a in order to prevent the escape of heating fluid from the interior of body portion 40a.

Eccentric reel member 36a is formed of a rigid cagelike member 50a concentrically mounted upon a rotatable supporting member 51a by means of bolts 52a. Rigid cagelike member 50a comprises the bar members 39a fixed at their supported ends to an external annular reinforcing rib 53a, by means of which said cagelike member 50a is mounted on rotatable supporting member 51a, and an annular reinforcing rib 54a fixed to the bar members 39a at their unsupported ends. Supporting member 51a is mounted by means of spaced antifriction bearings 51a upon frame member 55a for rotation about an axis disposed in the desired offset and inclined relation with respect to the axis of rotation of concentric member 35a.

An externally toothed member 64a on rear closure member 42a engages an annular internally toothed member 63a on supporting member 51a, thus driving eccentric reel member 36a from concentric reel member 35a.

Drive shaft 37a is journaled in frame member 55a by means of bearing 61a disposed at the unsupported end of said frame member and by means of antifriction bearing 62a supported in a cross member 94 fixed to the spaced, longitudinally extending members 95 forming part of frame member 55a. It is positioned against endwise movement between collar 49a and collar 96 bearing against the inner race of antifriction bearing 62a. Drive shaft 37a is rotated by means of a bevel gear 65a mounted on said shaft between the longitudinally extending members 95. Bevel gear 65a meshes with a corresponding gear on inclined drive shaft 67.

Frame member 55a is provided with a flanged 65 portion 58a adapted to fit closely into and to be held in a cup member 59a fixed to the frame of the apparatus, whereby reel 14 is demountably supported in the apparatus.

The means for circulating heating fluid through the reel is generally similar to that above described. A fitting 97 mounted on the longitudinally extending members 95 of frame member 55a is provided with two compartments 68a and 69a. The drive shaft 37a projects into the

forward compartment 68a, while tube 84a, fixed in said hollow drive shaft 37a, extends into rear compartment 69a. Suitable plugs 47a and 85a are provided in said hollow drive shaft 37a to support inner tube 84a and prevent fluid from passing directly from hollow drive shaft 37a to inner tube 84a and vice versa. Suitable sealing means 11a are provided to prevent the escape of fluid from compartment 68a past drive shaft 37a or from compartment 69a into compartment 68a.

Heating fluid is supplied to compartment 68a through opening 78a and passes through ports 81a into the space between the inner tube 84a and the inner surface of hollow drive shaft 37a. The fluid passes out of said hollow drive shaft through ports 82a into the interior of body portion 40a of concentric reel member 35a. After circulating through said body portion, the fluid passes through ports 83a into the interior of inner tube 84a, whence it is discharged into the rear compartment 69a. The heating fluid passes out of said compartment through port 87a.

In the embodiment of the invention shown in Figure 2, heating fluid is supplied through conduit 89a which extends longitudinally of the machine. Tube 79a conducts the heating fluid from conduit 89a to entrance port 78a of reels 14. After the heating fluid has circulated through the reel, it passes through a tube 88a connected to the discharge port 87a to a discharge conduit 90a extending longitudinally of the apparatus. The heating fluid for reels 14 may comprise any suitable medium such as hot water, steam or other suitable fluid.

Using the methods and apparatus of the invention, it is possible to produce by a continuous process multiple filament viscose artificial silk thread having a highly uniform residual shrinkage capacity in the neighborhood of one per cent. The precise value in a given case depends upon various factors, but will usually be found to be within the range between three quarters and one and one quarter per cent. All other physical and physico-chemical characteristics are likewise extremely uniform. The example which follows is illustrative of the practice of the invention, the apparatus employed being that illustrated in Figures 1 and 2.

Viscose artificial silk thread of 150 denier, 40 filaments, is delivered at a speed of 68 meters per minute to reel 12, which is preferably made of aluminum. Still in the gel state when it is passed to the reel, the thread has a moisture content of approximately 400%. The thread is at ordinary room temperatures before it is taken up by the reel, which is heated to at least 115° C.; so that it is subjected on the reel to a sudden rise in temperature of approximately 90° C.

At the high temperature to which the reel is heated, the moisture is rapidly driven from the thread. The thread advances several turns before it begins to shrink; accordingly, the reel is of substantially cylindrical configuration for about 1.5" lengthwise of its thread-bearing periphery, measuring from the supported end of the reel. From this portion, where the reel is of 5" diameter, the reel is tapered to a diameter of approximately 4.9", this in order to allow for shrinkage of the thread during the phase of the drying operation during which the internal moisture is removed from the thread.

The last few turns of thread at the unsupported end of the reel; i. e., for a distance of about $\frac{1}{4}$ " lengthwise of the periphery of the reel, are rewet with an aqueous rewetting liquid after the thread

has been dried but while it is still at an elevated temperature. The rewetting is preferably done by applying the liquid to the thread at the rate of about 30 cc. per minute, the rate being determined by the amount of moisture which can be reabsorbed by the thread. The thread will ordinarily absorb the rewetting liquid only until it attains a moisture content slightly in excess of 200%.

10 The application of the rewetting liquid results in elongation of the thread, wherefore reel 13 is 5" in diameter at the portion on which the thread starts. It revolves at the same angular velocity as the preceding reel, the difference between the 5" diameter of reel 13 and the 4.9" diameter of reel 12 being sufficient to allow the thread to pass from reel 12 to reel 13 without slackness or tension. Reel 13, being formed of hard rubber or other plastic material, is not heated, but is of the same type as reels 6 to 11, inclusive. The reel is of substantially cylindrical configuration throughout its length, having a thread-bearing periphery in the neighborhood of 5" long.

As it leaves reel 13, the thread has a highly uniform moisture content of approximately 200%, based on the weight of the thread.

Reel 14, on which the final drying of the thread is accomplished, is ordinarily designed to be heated to a temperature not greater than 100° C., depending upon the nature of the thread being dried. In the instant example, it is heated to about 78° C. An initial length of 1.5" of the periphery of the reel nearest the supported end is substantially cylindrical. The next 3.5" of the length of the reel is tapered to allow for shrinkage of the thread in the absence of substantial tension. The last 1.5" is substantially cylindrical to allow for complete drying of the thread after completion of the shrinkage. Like reel 12, reel 14 is of aluminum.

Under these conditions, no loops form in the thread during the second drying operation, this even though the thread is permitted to shrink freely. The thread is characterized by straight filaments of highly uniform characteristics. By contrast, thread which is dried only once, even with substantially unrestrained shrinkage, is characterized by loops in its filaments which not only impair the appearance of the thread but also introduce difficulties in forming the thread into fabric. This fact, together with the fact that on rewetting the thread absorbs at most considerably less than its original moisture content; e. g., in the neighborhood of one-half of its original moisture content, indicates that a change in the structure of the thread takes place in the course of the first drying operation.

Both the methods and forms of apparatus above described as embodying the invention are susceptible of various modifications without departing from the spirit of the present invention. For example, more drying operations, with intermediate rewetting, may be employed than those specifically disclosed and other means for and methods of rewetting than those illustrated may be used. Either as disclosed or as modified, the illustrated methods and forms of apparatus may be employed for other uses; for example, the drying of materials other than textile thread per se. The term "thread" in the appended claims is intended to include similar materials capable of being operated on and handled according to the present invention.

It is intended that the patent shall cover, by

suitable expression in the appended claims, whatever features of patentable novelty reside in the invention.

What is claimed is:

1. In the manufacture by the viscose process of multiple filament artificial silk thread having highly uniform shrinkage characteristics, the method of uninterruptedly producing a continuous length of thread characterized by a residual capacity to shrink in the neighborhood of 1% comprising successively performing in one continuous sequence of operations the several steps of extruding viscose into a coagulating bath to form the thread; subjecting the thread so formed to liquid processing treatment; drying the processed thread from the gel state; rewetting the dried thread; storing the rewetted thread under conditions permitting excess liquid to drip therefrom; redrying the thread under conditions such that the residual shrinkage capacity of the thread may be fixed at the desired value, meanwhile supporting the thread in the absence of substantial tension in such manner that the thread is free to shrink virtually without restraint; and, after completion of the re-drying operations, collecting the thread in package form, each of said steps other than the first and last being performed on the thread while it is traveling endwise in extended form.
2. A method as in claim 1 including the step of drying the thread from the gel state while supporting it in the absence of substantial tension.
3. A method as in claim 1 including the steps of drying, rewetting and redrying the thread while supporting it in such manner that the tension in the thread remains substantially constant.
4. A method as in claim 1 including the step of drying the thread from the gel state while supporting it rigidly over substantially its entire length to thereby cause tension to develop in the thread and to overcome the inherent tendency of the thread to shrink.
5. In the processing of multiple filament vis-

cose artificial silk thread pursuant to a method in which freshly spun thread is passed in sequence over a series of separate thread-advancing reels on each of which the thread is continuously but temporarily stored in a large number of generally helical turns, the steps of heating the thread from the gel state to a condition of substantial dryness while it is stored on a first of said series of thread-advancing reels; passing the dried thread to and rewetting it on a second of said series of thread-advancing reels on which the re-wetted thread is stored in sufficient length so that over part of the helix, on which part no liquid is applied to the thread, the re-wetting liquid can drip therefrom; and passing the re-wetted thread to and reheating it to a condition of substantial dryness on a third of said series of thread advancing reels, meanwhile supporting it in the absence of substantial tension in such manner that it is free to shrink virtually without restraint.

6. In the processing of multiple filament viscose artificial silk thread pursuant to a method in which freshly spun thread is passed in sequence over a series of separate thread-advancing reels on each of which the thread is continuously but temporarily stored in a large number of generally helical turns, the steps of heating the thread from the gel state to a condition of substantial dryness while it is stored on a first of said series of thread-advancing reels; re-wetting the dried thread, passing it in the meanwhile to a second of said series of thread-advancing reels on which the re-wetted thread is stored in sufficient length so that over part at least of the helix the re-wetting liquid can drip therefrom; and passing the re-wetted thread to and re-heating it to a condition of substantial dryness on a third of said series of thread-advancing reels, meanwhile supporting it in the absence of substantial tension in such manner that it is free to shrink virtually without restraint.
